UNITED STATES PATENT OFFICE.

JOSEPH F. KIESWETTER, OF TOLEDO, OHIO.

CARPET-CLEANER.

SPECIFICATION forming part of Letters Patent No. 366,961, dated July 19, 1887.

Application filed December 21, 1886. Serial No. 222,226. (No model.)

To all whom it may concern:

Be it known that I, JOSEPH F. KIESWETTER, a citizen of the United States, residing at Toledo, in the county of Lucas and State of Ohio, have invented new and useful Improvements in Carpet-Cleaners, of which the following is a specification.

This invention relates to a device for beating and removing dust and dirt from carpets and similar fabrics by an operation of revolving and tumbling; and it consists of a revolving open-work cage peculiar in its construction of angles and apartments, as hereinafter described, and set forth in the claim; and the object of my invention is to remove the dust and dirt from the carpet or other fabric with the least amount of wear and tear and injury to it while it is being cleaned by this operation. I accomplish this object by the mechanism illustrated in the accompanying drawings, in which—

Figure 1 is a left-hand side elevation of my machine as Fig. 2 represents it. Fig. 2 is a face view, the left-hand end of which is represented in Fig. 1. Fig. 3 is a cross-section of the revolving cage, taken on the plane XX, Fig. 2, showing the internal construction of some of the sections, all of which are alike.

In all of these views like letters refer to like parts.

A A are benches or knees, one on each side of the machine, to which are secured by bolts the bearing-boxes B B. To these boxes are fitted the bearings or gudgeons C C. These gudgeons terminate in plates or flanges c c, by which they are secured to the arms E of the cage.

The cage consists of a heavy substantial frame-work secured together by laps and bolts or mortises and tenons, to which the lighter slats and parts are secured in a substantial manner, as shown.

E E are a series of radial arms secured by bolts near the center end to the gudgeon plate c. To these arms E are secured, near their outer ends, a series of branch or angular arms, F F. These two series of arms, with their branches, one on each side, are connected by a series of outer cross-rails, h h, and a series of inner cross-rails, i i—the cross-rails h h at the extremity of the arms E E, and the cross-rails i i at the intersection of the branch arms F F with the arms E E. This frame is filled in on the sides with radial slats e e, 55 between the arms E E, as close as may be de-

sired. The edge or face of the cage is also filled in with slats n n between the cross-rails h h and i i, as close as may be desired, one section being provided with hinges and left loose for a door, L, through which the carpet or other fabric to be cleaned is taken in and out.

D D are rims secured to the arms E E by bolts, which form pulleys, for the purpose of receiving belts to revolve the cage by steam or other power.

I design to cover the face of the cage with wire-cloth, to prevent small pieces of carpet or other fabric from passing out between the slats when the cage is in motion, a section of which is shown in Figs. 2 and 3, (marked K.) By this construction of a cage the pockets P P, formed on the inside of the cage, retain the carpet or other fabric when in motion and carry it up and cause it to drop almost perpendicularly through the cage, thus causing very little wear to it by sliding on the inside parts of the cage while it is being cleaned.

The cage revolves in the direction indicated by the darts and dotted lines. By this system of revolving and tumbling, the dust and dirt is loosened from the carpet, and the centrifugal motion given to the air by the motion of the cage drives it out and cleanses the carpet.

Having thus described my machine in its mode of working and its construction, I am aware that carpet-cleaners have been constructed having revolving cages with bearings supported by boxes and benches and driven by power. I therefore do not claim such a construction, broadly; but

What I do claim as my invention, and desire to secure by Letters Patent, is—

In a carpet-cleaner, a cage provided with 95 bearings C C and a series of radial arms, E E, a series of branch arms, F F, a filling of radial slats, e e, pulleys D D, a series of alternate cross-rails, h h, a series of alternate inner cross-rails, i i, with a filling of cross-slats, n n, and a covering of wire cloth, K, substantially as described.

In testimony whereof I have hereunto set my hand in the presence of two subscribing witnesses.

JOSEPH F. KIESWETTER.
